W. P. STUNZ.

TELEPHONIC INSTRUMENT, INCLUDING TRANSMITTERS.

APPLICATION FILED APR. 13, 1911.

1,030,551.

Patented June 25, 1912.

FIG. 1.

FIG. 2.

UNITED STATES PATENT OFFICE.

WILLIAM PRESTON STUNZ, OF LANSDOWNE, MARYLAND, ASSIGNOR TO GEORGE REGESTER WEBB, OF BALTIMORE, MARYLAND.

TELEPHONIC INSTRUMENT, INCLUDING TRANSMITTERS.

1,030,551.

Specification of Letters Patent. Patented June 25, 1912.

Application filed April 13, 1911. Serial No. 620,960.

To all whom it may concern:

Be it known that I, WILLIAM PRESTON STUNZ, a citizen of the United States, residing at Lansdowne, in the county of Baltimore and State of Maryland, have invented certain new and useful Improvements in Telephonic Instruments, Including Transmitters; and I do declare the following to be a full, clear, and exact description of the invention, such as will enable others skilled in the art to which it appertains to make and use the same, reference being had to the accompanying drawings, and to the letters and figures of reference marked thereon, which form a part of this specification.

My invention relates to telephonic instruments, more particularly to microphone or granular carbon transmitters.

Each grain or granule of carbon in telephone instruments constitutes a resistance unit and when the granules are subjected to an excess or overcharge of current heat is generated and when the granules thus become over-heated their resistance capacity is proportionately lowered. Accordingly the current carrying capacity of the granular carbon is limited or diminished relatively as the degree of resistance is lowered occasioned by the over-heating of the carbon. It follows that if this over-heating of the carbon granules is prevented the maximum current carrying capacity of the carbon granules is obtained, and to the extent that the carbon granules are rendered capable of carrying a heavier current to that extent the load to be carried on the line can be increased and a fall of voltage due to lowering the resistance of the carbon granules is overcome and this results in making it possible to employ a greater number of instruments on the line.

My invention accordingly has primarily for its object to maintain a normal or low condition of temperature in the carbon granules under conditions in which otherwise the current would over-heat the carbon granules and lower their resistance, and this I effect by the application of a cooling agent to act upon the carbon granules so as to keep down their temperature and thus prevent their over-heating and consequent lowering of their resistance and by such means making it possible to carry a heavier current on the line.

To the accomplishment of the foregoing

I have selected for the purposes of illustration a multiplex microphone or granular carbon transmitter having embodied therein one form of the invention but without meaning however to restrict the invention to such particular form or to such particular use except as may be specified as it is the purpose to cover the invention comprehensively in whatever form or to whatever kind of instrument employing granular carbon as the resistance it may be used.

In the accompanying drawings illustrating one form of the invention: Figure 1 represents a front elevation of several individual transmitters constituting a multiplex transmitter; Fig. 2 is a vertical section through two of the individual transmitters and having my invention applied thereto; Fig. 3 is a partially vertical sectional view through the cooling chamber, on a larger scale than the other views; and Fig. 4 is an end view of the cooling chamber with its face or electrode omitted.

In Fig. 1 of the drawing there is illustrated a multiplex transmitter of the form shown in U. S. Patent No. 943,115 granted Dec. 21, 1909 to George R. Webb, as assignee, and in which the movable electrodes of the individual transmitters are connected to the branch arms of an oscillating member 1 so that when said member oscillates in one direction the granular carbon in two of the individual transmitters is compressed and the carbon in the other two transmitters permitted to loosen up, and in the oscillating of the member in the other direction the granular carbon in the transmitters previously loosened up is compressed while that in the other transmitters is loosened up, and in which also is shown a circuit in which two of the movable electrodes are legged to a branch wire 2 of the line, and the movable electrodes of the other two individual transmitters legged to a branch wire 3 of the line while the immovable electrode of one individual transmitter is connected by wire 4 with the immovable electrode of one of the other individual transmitters, as illustrated, said wire being also connected with one pole of a battery or other source of electrical energy. The other two individual transmitters are connected by a wire 5 leading from their rear or immovable electrodes which wire also leads to the other pole of the battery or source of electrical

energy. This particular form of multiplex transmitter however, and the circuit described, indicates merely one form of transmitter and circuit in which my present invention may be employed and is given merely as an illustration of one form in which the invention may be employed without limiting the invention to such form. In Fig. 2 of the drawing is illustrated a vertical section through two individual transmitters such as shown in Fig. 1 of the drawing but having applied thereto the present invention in one form, and, so far as I have knowledge at present, the best or preferred form for its application.

The present invention consists in providing means for preventing the over-heating of the carbon granules in the working of the device so that their maximum efficiency is maintained and a heavier electrical current may be employed so that the load to be carried on the line may be increased.

One form of embodiment of this invention is illustrated in Fig. 2 of the drawing in which the numeral 6 designates the cup for holding the granular carbon 7 and formed of felt or other suitable material while 8 indicates a movable electrode and 9 a fixed or stationary electrode. This fixed electrode is carried by a shell or hollow cup 10 of suitable material and may have the fixed electrode secured thereto by overlapping the edges of the cup on to the edges of the electrode. This shell or cup forms a hollow chamber adapted to receive a suitable cooling agent, which for illustration may be water although any other suitable cooling fluid or agent may be employed. The cooling agent in this shell or chamber contacts one face of the fixed electrode and its cooling influence is transmitted through the electrode to the granular carbon so that the temperature of the granular carbon is kept comparatively low under various charges of current, and this cooling of the granular carbon prevents lowering its resistance properties which ordinarily is reduced or diminished under an excess or over-charge of current and to the extent to which such resistance has been reduced by over-heating impairing the efficiency of the resistance properties of the carbon granules. By cooling the carbon granules it is also made possible to employ a heavier current so that the load to be carried on the line may be correspondingly increased and thus making it possible to employ a greater number of instruments on the line having the maximum of efficiency. The cooling agent may be supplied from any suitable source to the cooling chamber 10 through a pipe or tube 11, which in practice will be connected with the supply pipe by a rubber or other insulating tubing, and will be discharged from the chamber 10 through pipe or tube 12, which likewise will

be connected by a rubber or insulating tubing with a discharge conduit. Both the supply and discharge pipes, for controlling or regulating the flow of the cooling agent through the chamber 10, may be provided with inlet and outlet valves or cocks suitably positioned but not illustrated as the same may be of any approved type and are not necessary to the working of the invention. For the purpose of causing the cooling agent to pursue a circuitous course in flowing through the chamber and thus attain better results, the interior of the chamber may be provided with a series of partitions 13 which are illustrated as extending cross-wise of the chamber and terminating at one edge short or back of the walls of the chamber so as to form a zigzag or circuitous passageway for the flow or passage of the cooling agent. The shell or cup constituting the cooling chamber is provided with a threaded stem 14 by which the chamber and associated parts may be supported from a suitable support 15. The opening in the support through which passes the stem may be provided with suitable insulating material 16 and to each side of the support may be placed insulating strips 17, and a nut 18 may be applied to the threaded stem so as to secure the parts together. These features however are matters of mere detail and may be varied at will without departing from the essential features of the invention.

While I have illustrated the invention as applied to a microphone or granular carbon transmitter, and have selected merely for purposes of illustration a multiplex transmitter of the form previously mentioned, yet it is to be understood that the invention is not in all its forms and uses confined or limited to the particular mode of its application illustrated, as the invention in its broadest scope contemplates a construction by which a cooling-medium is circulated through a chamber separated by an electrode from a body of granular carbon so that by the continuous discharge and replacement of the cooling-medium the maximum of resistance in the granular carbon is maintained by preventing the over-heating of granular carbon in instruments where such material is employed so as to obtain the maximum efficiency of the granular carbon so far as its resistance properties are concerned and so as to make it possible to employ a heavier current than otherwise without lowering the resistance properties by the current employed. This as previously stated also makes it possible to employ a heavier current so that the load to be carried on the line may be increased and a larger number of instruments employed without impairment in their maximum efficiency. Accordingly it will be understood that while the invention may be employed in the type of in-

struments illustrated and referred to with excellent results yet the invention contemplates its employment wherever it is desirable to prevent the lowering of the resistance properties of the carbon by over-heating or an excess of electrical current.

Having described my invention and set forth its merits what I claim is:—

1. In an instrument employing granular carbon as a resistance, the combination with the granular carbon, of a cooling chamber, and means forming a circuitous passageway within the chamber.
- 10 2. An instrument employing granular

carbon as a resistance, comprising a carbon retaining chamber, electrodes on opposite sides of the carbon, a cooling chamber at one face of one of the electrodes, a circuitous passageway within said chamber and means for supplying and withdrawing a cooling agent from said chamber.

In testimony whereof I affix my signature in presence of two witnesses.

WILLIAM PRESTON STUNZ.
